LABELING APPARATUS

George W. von Hofe, Bound Brook, N. J., assignor
to New Jersey Machine Corporation, Hoboken,
N. J., a corporation of New Jersey

Original application May 16, 1940, Serial No.
335,464. Divided and this application Septem-
ber 4, 1941, Serial No. 409,451

4 Claims. (Cl. 91—16)

The invention relates to labeling apparatus embodied in labeling machines and more particularly to labeling apparatus which includes label carrying means movable in a given manner for instance to transfer the labels from a label supply or pick-up station to a label applying station for application to the articles for which said labels are designed. The invention has for its object to provide novel means whereby the travel of the label carrying means is temporarily arrested at an intermediate point of its travel, as for instance a predetermined point between the aforesaid label supply or pick-up station and the label applying station. The invention contemplates further the provision of novel locking means whereby the position of said label carrying means at the arresting point is definitely predetermined and whereby said label carrying means is temporarily locked in said position with recurrent accuracy throughout repeated operative steps during an operative period of the labeling machine.

Other more specific objects will appear from the description hereinafter and the features of novelty will be pointed out in the claims.

This application is a division of another application filed by me in the United States Patent Office on May 16, 1940, Serial No. 335,464, and issued on April 28, 1942 as Patent No. 2,281,-397.

In the accompanying drawings, which illustrate an example of the invention and its application without defining its limits,

Fig. 1 is a side elevation partly broken away and in section, of a labeling machine with the novel arresting and locking means embodied therein;

Fig. 2 is an opposite side elevation of said labeling machine including the novel arresting and locking means with parts of the labeling machine unnecessary to the illustration of said means omitted;

Fig. 3 is a front elevation of the labeling machine and the novel arresting and locking means, and

Fig. 4 is an enlarged fragmentary view of the novel locking means.

For purposes of illustration and description the novel means are shown in a labeling machine of the type in which the label carrying means is reciprocated over a horizontal path between two opposite terminals as exemplified for instance by a label pick-up station and a label applying station. It is to be understood that the selected labeling machine and the specific form

of the arresting and locking means shown therein are in no sense intended to define the limits of the invention.

The labeling machine shown in the drawings comprises a suitable frame 10 on which a supply of labels 11 is supported in the form of a stack located in a container or hopper 12 mounted in any conventional manner on the frame 10 at the label pick-up station of the machine. 5 Suitable provision is made in the customary manner for periodically elevating the stack of labels 11 in the container 12 to restore the upper end of said stack to a predetermined level; as the means whereby this periodical elevation of the 10 stack of labels 11 is accomplished may be of any existing type and as said means per se does not constitute a part of the novel arresting and locking means, it has not been deemed necessary to show said elevating means in detail. At 15 the label applying station the machine is provided with a conventional support 13 suitably mounted on the frame 10 or otherwise arranged for supporting the articles to be labeled, in label receiving position at said applying station. 20 The labeling machine further includes carrying means for transferring the labels 11 in individual succession from the pick-up station to the applying station for application to the articles on the support 13 thereof. 25 As shown in the drawings, the label carrying means is of the suction operated type and includes a carriage 14 slidably mounted upon a horizontal guide rail 15 supported on the frame 10 in any convenient manner. The carriage 14 30 is reciprocated on the rail 15 between two opposite terminals exemplified in the instant case by the label pick-up station at which the supply of labels 11 is located, and the label applying station at which the support 13 for the articles to be labeled is positioned. For reciprocating the carriage 14 on the rail 15, an arm 16 35 is fixed upon a shaft 17 suitably journaled on the frame 10, said arm 16 being yieldingly connected with the carriage 14 by means of a coupling rod 18 and coil springs 19. The shaft 17 40 is operatively rocked on its axis by means of a toothed segment 20 which meshes with a rack vertically movable in a guide 22 suitably located upon the frame 10. The rack 21 forms part of 45 an operating member 23 formed at its lower end to straddle a driving shaft 24 rotatably mounted in conventional bearings on the frame 10. The operating member 23 carries a roller 25 in operative engagement with a cam 26 fixed upon the 50 shaft 24. 55

As the shaft 24 and the cam 26 are rotated, the latter will in co-operation with the roller 25 operate the rack 21 vertically to thereby rock the segment 20 and its shaft 17 on the axis of the latter. This will oscillate the arm 16 and through the medium of the coupling rod 18 will cause the carriage 14 to be moved backward and forward or, in other words, to be reciprocated on the rail 15 between the aforesaid two opposite terminals.

The carriage 14 serves as a support for a vertically movable member 27a provided at its lower end with a suction head 27 connected by means of a preferably flexible tube 28 with a source of suction, it being understood that provision is made in any well-known way to control the suction in the suction head 27 in proper synchronism with the other operations of the machine. When the carriage 14 is temporarily at rest, at the opposite terminals as exemplified by the pick-up station, and the label applying station, the suction head 27 is lowered and raised on the carriage 14 to pick up individual labels from the supply stack and to deposit said labels upon the articles on the support 13 at the label applying station. These operations of the suction head may be accomplished by conventional means indicated at 29 and requiring no detail description as per se it forms no part of the instant invention. As the carriage 14 travels in one direction on the rail 15, that is in the present instance toward the label applying station, the travel of said carriage will be temporarily arrested at a predetermined intermediate point between the label pick-up station or label applying station, or in other words, between the two opposite terminals for the purpose for instance of permitting a code character or designation to be imprinted or otherwise produced upon the label carried by the suction head 27 at the time; the imprinting or other device 30 is diagrammatically indicated in dotted lines in Fig. 3 of the drawings. Subsequently to the temporary rest period of the carriage 14, the travel thereof toward the label applying station is continued. The means whereby the aforesaid temporary arresting of the travel of the carriage 14 is brought about comprises a dwell section *a* with which the cam 26 is provided and which is arranged in co-operation with the roller 25 and the operating member 29 with its associated elements, to arrest the movement of the carriage 14 on the rail 15 and to retain said carriage in this position of rest for a predetermined time period sufficient for instance to permit the aforesaid code character or designation to be imprinted on the particular label carried at the time.

For the purpose of locking the carriage 14 and the suction head 27 carried thereby in the arrested position with recurrent accuracy, a locking means is provided which operates in predetermined synchronism with the arresting means and insures a temporary stoppage of the suction head and carriage always at exactly the same predetermined point. This result is secured regardless of slight variations in the position at which the carriage and suction head are temporarily arrested by the dwell section *a* of the cam 26 and the elements co-operating therewith; any adjustment in the arrested position by the action of the locking means made necessary because of the aforesaid variations is possible because of the coil springs 19. In the illustrated example, the locking means under discussion consists of a locking recess 31 provided at a suitable point 75

on the suction head 27 and preferably tapering inward for co-operation with a movable locking device shown in the form of a locking bolt 32 having a tapered free end 33 slidably mounted in a guide 34 carried by a bracket 35 suitably secured upon the frame 10. A pin 36 carried by the locking bolt 32 projects outwardly through a slot 37 formed in the guide 34 and connected with the forked end 38 of a bell crank lever 39. The latter is pivotally mounted at 40 upon the bracket 35 and at 41 is pivotally connected with one end of an operating rod 42 the other end of which is pivotally connected at 43 with an arm 44 fixed upon a rocker shaft 45. This shaft is journalled in a bearing 46 fixed by means of a bracket 47 upon the frame 10; the shaft 45 further carries a lever 48 provided at its free end with a roller 49 held in contact with a cam 50 by means of a spring 51. The cam 50 is secured upon the shaft 24 and includes a relatively low concentric section *b* and a relatively high concentric section *c* as shown in Fig. 1.

The labeling machine further includes adhesive applying means 51a of conventional form 25 whereby a coating of adhesive is applied to each label as it is carried by the suction head 27 or its equivalent toward the label applying station. The arrangement is such that the suction head 27 occupies a raised position during the return 30 movement of the carriage 14 toward the pick-up station or equivalent terminal; an arrangement of the indicated type is shown in my United States Patent No. 2,227,816 of January 7, 1941. In addition the machine may include a pressure 35 developing means 52 of any well-known type, as well as any other features commonly found in such machines.

In the position of the parts shown in the drawings the carriage 14 and the suction head 27 are 40 shown as temporarily arrested at an intermediate point between the opposite terminals as represented by the pick-up station and the label applying station and are temporarily locked in this position by the aforesaid locking means. As the 45 operation of the labeling machine continues, and subsequent for instance to the imprinting or other production of a code character or designation on the particular label carried by the suction head at the time, the roller 49 of the lever 50 48 will pass from the low section *b* of the cam 50 to the high section *c* thereof. The lever 48 will thereby be pivotally moved downwardly in Fig. 1 against the tension of the spring 51 and will rock the shaft 45 in its bearing 46 to correspondingly 55 move the arm 44 in a downward direction. This will pull the rod 42 downwardly and will pivotally actuate the bell-crank lever 39 in a manner to shift the locking bolt 32 to the right in the guide 34 in Fig. 3 to thereby withdraw the tapered end 33 of the locking bolt 32 from the locking recess 31 of the suction head 27. In proper operated 60 synchronism with these operations the roller 25 of the operating member 29 will pass from the dwell section *a* of the cam 26 whereby the rack 21 will be moved in a continuing upward direction to thereby operate the toothed segment 20 in a manner to swing the arm 16 to the left in Fig. 1 whereby movement of the carriage toward the label applying station is resumed and continued 65 until this station is reached. Subsequently to the deposit of the particular label upon the article at said labeling point, the apparatus is operated to cause the parts to be operated in return directions and to shift the carriage 14 with its suction head 27 in a raised position back to the label 70 75

pick-up station to there pick up the next succeeding terminal label from the supply stack after which the carriage 14 and suction head 27 are again moved toward the label applying station. As the roller 25 reaches the dwell section *a* of the cam 28 the travel of the carriage 14 and its suction head 27 will again be temporarily arrested at the aforesaid intermediate point between the opposite terminals. During the movement of the carriage 14 toward the label applying station, the label carried by the suction head 27 will pass in adhesive receiving relation to adhesive applying means 51a to receive an application of adhesive therefrom. The adhesive applying means 51a is effective at a point in predetermined relation to the point at which the travel of carriage 14 is temporarily arrested, and the application of adhesive to the carried label preferably takes place in advance of the aforesaid temporary arrest of the travel of said carriage 14. In proper synchronism with these operations the roller 49 will pass from the high section *c* of the cam 50 to the low section *b* thereof. The lever 48 and arm 44 will thereby be pivotally actuated to develop an upward push in the rod 42 which in turn will swing the bell crank lever 39 in a manner to shift the locking bolt 32 to the left in the guide 34 in Fig. 3. This will cause the tapered end 33 of said locking bolt 32 to enter the correspondingly tapered locking recess 31 of the suction head 27 and thereby temporarily lock the latter and with it the carriage 14 in the arrested position. Because of the tapered form of the locking recess 31 and the tapered end 33 of the locking bolt 32, the said tapered end 33 and tapered recess 31 in co-operation with each other will develop a camming force whereby the suction head 27 is set with recurrent accuracy in the arrested position. In other words, any slight variations in this position resulting from the action of the arresting means will be corrected. At the end of the predetermined period of rest the locking bolt 32 will be withdrawn from the locking recess 31 and the travel of the carriage 14 and suction head 27 toward the label applying station will be resumed. The aforesaid cycle of operations will be repeated throughout an operative period of the machine.

With the novel arrangement it is possible to temporarily arrest the travel of the label carrying means at a predetermined intermediate point for a given operative purpose, such as set forth hereinbefore, and to then resume and continue the travel of said carrying means to a terminal. To insure recurrent accuracy in the arrested position of the carrying means the simple and novel locking means described herein operates in proper synchronism with the aforesaid arresting means. The novel arresting and locking means may be readily installed in existing labeling machines with a minimum of expense and with little effort, and require no particularly expert supervision in their operation.

Various changes in the specific forms shown and described may be made within the scope of the claims without departing from the spirit of the invention.

I claim:

1. In a labeling apparatus, the combination of a vacuum head movable in a horizontal plane for transferring successive labels from a pick-up station to an applying station in said apparatus, operating means for moving said vacuum head with a label carried thereby in said horizontal

plane and being arranged to temporarily arrest the movement of said vacuum head at an intermediate point of its movement for the performance during said temporary arrest, of an associate step in the cycle of operations on the exposed surface of the successive labels transferred by said vacuum head, and an adhesive-applying device for applying adhesive to the exposed surface of each label carried by said vacuum head during the movement of the latter in said plane.

2. In a labeling apparatus, the combination of a label carrying means reciprocable over a given path between two terminals to transfer successive labels from one terminal to the other, operating means for reciprocating said label carrying means between said terminals, said operating means without interruption of its own operation being arranged to temporarily arrest the travel of said label carrying means in the label transferring direction at a predetermined point between said terminals for the performance, during said temporary arrest, of an associate step in the cycle of operations on the exposed surface of the successive labels transferred by said label carrying means, and to effect a continuous travel of said carrying means in the opposite direction, and means for applying adhesive to a label carried on said label carrying means, said adhesive applying means being effective at a point in predetermined relation to the point at which the travel of said label carrying means is temporarily arrested.

3. In a labeling apparatus, the combination of a label carrying means reciprocable over a given path between two terminals to transfer successive labels from one terminal to the other, operating means for reciprocating said label carrying means between said terminals, said operating means without interruption of its own operation being arranged to temporarily arrest the travel of said label carrying means in the label transferring direction at a predetermined point between said terminals for the performance, during said temporary arrest, of an associate step in the cycle of operations on the exposed surface of the successive labels transferred by said label carrying means, and to effect a continuous travel of said carrying means in the opposite direction, and means for applying adhesive to a label carried on said label carrying means, said adhesive applying means being effective at a point in advance of the aforesaid temporary arrest of the travel of said label carrying means.

4. In a labeling apparatus, the combination of a label carrying means reciprocable over a given path between two terminals to transfer successive labels from one terminal to the other, operating means for reciprocating said label carrying means between said terminals, said operating means without interruption of its own operation, being arranged to temporarily arrest the travel of said label carrying means in the label transferring direction at a predetermined point between said terminals for the performance, during said temporary arrest, of an associate step in the cycle of operations on the exposed surface of the successive labels transferred by said label carrying means, means for temporarily locking said label carrying means in its arrested position, and means for applying adhesive to a label carried on said carrying means prior to the temporary locking of the latter in its arrested position.
